There's a tireless worker who loves to carry, keep one handy and you'll never tarry.

Can't move all your stuff from here to there, load this one and its done with care.

Very loose footing is always a struggle, this crawler's sure footed and an easy "tuggle".

Hauling your stuff is no longer tough, for this tender brute is a real gym buff.

Sand Crawler is a very real treat, to proudly show all the folks that you meet.

Be courteous of folks when here and there, let them try a tug if you think its fair.

If its' a stretch to get there on the dot, this crawler will help you reach your spot.

So many things we want at the beach, crawler will help make the beach within reach.

Umbrellas, blankets, your favorite cooler, crawler's your pal and you'll travel smoother.

Sand Crawler is a best friend indeed, Sand Crawler's a pal, carrying all your needs.

This hauler has a superior crawl, sure footed and safe and you'll rarely stall.

Got tackle and buckets, bait and more, with a crawler in tow it's no longer a chore.

If fishing is your very great pleasure, a crawler will help haul home your treasure.

No people, no pets, no fingers or toes, the Crawler is only for stuff on the go.

No coasting, no surfing or horsing around, the Crawler is not for fooling around!

No overloading and make stuff secure, Sand Crawler is trustworthy but you must be sure.

Who'll help with your burdens today? Only one thing to say! Sand Crawler!
